Specification of Letters Patent.

Patented Mar. 4, 1913.

Application filed February 10, 1912, Serial No. 676,731. Renewed January 24, 1913. Serial No. 744,036.

To all whom it may concern:

Be it known that we, JULIAN PIOTROWSKI and ANTONI KILINSKI, both subjects of the Czar of Russia, and residents of the city of 5 New York, borough of Manhattan, in the county and State of New York, have invented a new and Improved Accumulator, of which the following is a full, clear, and exact description.

10 The object of the invention is to provide a new and improved accumulator or storage battery arranged to provide a large surface in a comparatively small space and to allow convenient escape of gases and precipitation of sediments.

For the purpose mentioned, use is made of alternating positive and negative electrodes, each formed of a series of laminated lead plates, insulating lead plates intermediate the electrodes, a casing adapted to contain the said electrodes and insulating plates, the casing being provided with interior guideways, and supporting bars of glass or other non-conducting material and 20 extending through the said electrodes and insulating plates, the terminals of the said supporting bars engaging the said guideways to suspend the electrodes within the casing.

25 A practical embodiment of the invention is represented in the accompanying drawings forming a part of this specification, in which similar characters of reference indicate corresponding parts in all the views.

30 Figure 1 is a side elevation of the accumulator, the section being on the line 1—1 of Fig. 2; Fig. 2 is a transverse section of the same on the line 2—2 of Fig. 1 parts being broken out; Fig. 3 is a plan view of the same; Fig. 4 is a reduced face view of one of the lead plates of an electrode; Fig. 5 is a face view of one of the insulating plates; Fig. 6 is an enlarged plan view of part of one of the electrodes. Fig. 7 is a perspective view of a portion of the bottom plate supporting the insulating plates and Fig. 8 is a perspective view of one of the slotted cross bars of the electrodes.

35 The casing A of the accumulator is made of hard rubber or other similar material, and the inner faces of the sides of the casing A are provided with vertically-disposed guideways B open at the top and adapted to receive and support suspending bars C, of 40 glass or other suitably insulating material,

the said bars extending transversely through positive and negative electrodes D, D' spaced from each other by insulating plates E, of hard rubber or a like material. By the arrangement described the positive and negative electrodes D and D' and the insulating plates E are suspended within the casing A.

45 Each of the electrodes D and D' is formed of a series of laminated lead plates D² D³, of 50 which the lead plates D² are provided with vertically-disposed corrugated ribs D⁴ for spacing the successive lead plates D², D³ apart to form circulating spaces. The plates D², D³ of each electrode are also provided with slots D⁵, preferably arranged in oblique direction and with the slots D⁶ of successive plates D², D³ extending in opposite directions so as to cross each other, as will be readily understood by reference to 55 the full and dotted lines in Fig. 1. The intersecting slots D⁵ form passages for the battery fluid. As shown in Fig. 2, the outside electrodes are negative electrodes D' and consequently the negative electrodes D' 60 exceed in number the positive electrodes D.

65 The upper ends of the plates forming the positive and negative electrodes are provided with upwardly-extending lugs D⁶, D⁷ engaging notched cross bars F, F' through 70 which extend transversely pins G, G' passing through the lugs D⁶, D⁷, and the said cross bars F, F' are provided with upwardly-extending binding posts F², F³ for connection with the electric conductors. A 75 cover H fits into the upper end of the casing A and rests on the upper ends of the guideways B, and the said cover H is provided with an apertured vent I for the escape of 80 gases from the casing A.

85 The insulating plates E are preferably perforated, as indicated in Fig. 5, and their lower ends fit into notches arranged in the top of a bottom plate J, made of hard rubber or other similar material, and resting on 90 transverse ribs K forming integral parts of the bottom of the casing A. The bottom plate J is provided on top with semicircular recesses J' connecting at the bottom with apertures J² to allow sediment or other impurities to pass through the recesses J' and apertures J² into the lower or bottom portion of the casing A.

95 The accumulator shown and described is 100 very simple and durable in construction and 105 110

provides an exceedingly large surface in a comparatively small space, and the individual parts can be readily removed and replaced in case they are worn out or injured.

5 Having thus described our invention, we claim as new and desire to secure by Letters Patent:

1. A storage battery, comprising a casing having its sides provided at the inner faces with vertical guideways extending from the top of the casing a distance downward, positive and negative electrodes arranged alternately and each formed of a series of laminated lead plates, insulating plates interposed between the said electrodes, and suspending bars of non-conducting material and extending through the said electrodes and insulating plates, the ends of the said bars engaging the said guideways to suspend 20 the electrodes and insulating plates in the casing.

2. A storage battery, comprising positive and negative electrodes arranged alternately and each formed of a series of laminated lead plates provided with lugs at the top, insulating plates intermediate the said positive and negative electrodes, posts having slotted cross bars engaged by the said lugs, attaching pins passing through the said cross bars and the said lugs, suspending bars of non-conducting material extending transversely through the said electrodes and insulating plates, and a casing provided with interior guideways engaged by the ends of the said suspending bars to suspend the electrodes and insulating plates in the casing.

3. A storage battery, comprising positive and negative electrodes arranged alternately and each formed of a series of laminated lead plates provided with lugs at the top, insulating plates intermediate the said positive and negative electrodes, posts having slotted cross bars engaged by the said lugs, attaching pins passing through the said cross bars and the said lugs, a bottom plate having recesses for the reception of the lower

ends of the said insulating plates, and a casing having ribs on the bottom for supporting the said bottom plate.

4. A storage battery, comprising positive and negative electrodes arranged alternately and each formed of a series of laminated lead plates provided with lugs at the top, insulating plates intermediate the said positive and negative electrodes, posts having slotted cross bars engaged by the said lugs, attaching pins passing through the said cross bars and the said lugs, a bottom plate having recesses for the reception of the lower ends of the said insulating plates, a casing having ribs on the bottom for supporting the said bottom plate, the said casing having its sides provided with vertical guideways extending from the top of the casing a distance downward, and suspending bars of insulating material and engaging the said guideways.

5. A storage battery, comprising positive and negative electrodes arranged alternately and each formed of a series of laminated lead plates provided with lugs at the top, insulating plates intermediate the said positive and negative electrodes, posts having slotted cross bars engaged by the said lugs, attaching pins passing through the said cross bars and the said lugs, a bottom plate in which the lower ends of the insulating plates are secured, the bottom plate having cup-shaped recesses on top and apertures leading from the bottoms of the said recesses to the underside of the bottom plate, and a casing having ribs on the bottom supporting the said bottom plate.

In testimony whereof we have signed our names to this specification in the presence of two subscribing witnesses.

JULIAN PIOTROWSKI.
ANTONI KILINSKI.
